UNITED STATES PATENT OFFICE.

GEORGE W. SCHIFFER AND ARTHUR L. KNIGHT, OF BUFFALO, NEW YORK.

PILLOW-SHAM HOLDER.

SPECIFICATION forming part of Letters Patent No. 400,122, dated March 26, 1889.

Application filed July 16, 1888. Serial No. 280,094. (No model.)

To all whom it may concern:

Be it known that we, GEORGE W. SCHIFFER and ARTHUR L. KNIGHT, of Buffalo, Erie county, New York, have jointly invented certain new and useful Improvements in Pillow-Sham Holders; and we do hereby declare that the following description of our said invention, taken in connection with the accompanying sheet of drawings, forms a full, clear, and exact specification, which will enable others skilled in the art to which it appertains to make and use the same.

This invention has general reference to pillow-sham holders; and it consists, essentially, in the novel and peculiar combination of parts and details of construction, as herein-after first fully set forth and described, and then pointed out in the claims.

In the drawings already mentioned, which serve to illustrate our said invention more fully and form a part of this specification, Figure 1 is a front elevation of a portion of a bedstead provided with our improved pillow-sham holder, the right-hand clamping mechanism therein shown being in section. Fig. 2 is a sectional plan in line $x x$ of Fig. 1. Fig. 3 is a perspective view of the clamping-arm with the clamping-screw. Fig. 4 is a front view of a portion of the clamping-bracket; and Fig. 5, a rear view of the same, like parts being designated by corresponding letters of reference in all the various figures.

The object of our present invention is the production of a simple and efficient pillow-sham holder that can be manufactured and sold at slight cost, and that when in use will not mar or deface the furniture to which it is applied. To accomplish this object we construct our pillow-sham holder substantially of two similar brackets, one being "right" and the other "left," so as to fit the respective posts of a bedstead. Each of these brackets is composed of the clamping-bracket A, having on one end a preferably bifurcated claw, B, and near the other end a lateral projection, C, provided with an aperture, c , for the object hereinafter to be referred to. The body of this clamping-bracket is longitudinally slotted at D, and the opposite edges of said slotted portion are notched or serrated, as shown at E. Within this slotted aperture operates or slides a clamping-arm, F, said arm being shown in

perspective in Fig. 3. This arm consists of an L-shaped body, one branch of which has a T-shaped head, G, and two catches, $a a'$, the latter catches engaging the serrations E in the clamping-bracket, as hereinafter to be explained. One of the arms of the L-shaped body F carries a thumb-screw, H, having a swiveling-head, h, faced with cloth or other similar material, b, so as to prevent the marring of the wood with which the swivel-head h comes in contact.

I I' are two wooden bars or slats held in sliding contact with each other by means of U-shaped loops J, (see Fig. 1,) one of which is secured to each bar and loops around the other, said bars being fitted with a wire frame, K, of the usual and well-known construction, to form the carriers upon, and to which the pillow-shams (not shown) are fastened in any desirable manner. The ends of the bars I I' are provided with sockets L L', projecting beyond the ends of said bars a sufficient distance to provide for a space or chamber, f, Fig. 1, to receive a coil-spring, M, which bears with one end against the end of the said bars I I', and with the other against the head of the projection C, said socket being driven upon the said bar with an easy driving fit, so as to cause it to retain its position by frictional contact. Through the aperture c in the head C and into the end of the bar I passes a screw, N, which, by being tightened, brings the head C into frictional contact with the spiral spring M, and thereby keeps the frame K in any position into which it may be placed. The bars I I' are slightly tapered on both ends, though not enough so to prevent the screws N from drawing the said bars farther into the sockets L L' in case it is desired to increase the frictional contact between the sockets and the projecting arms C of the brackets A. In the drawings the taper of these parts is somewhat exaggerated for the purpose of showing that they are taper. The bars I I' are made adjustable in length in the usual and well-known manner to adapt this device to bedsteads of varying widths.

The inner faces of the brackets A are cloth-lined at O to prevent scratching or marring of the bed-posts P. By constructing the brackets A with the clamping-arm F, as described, we are enabled to fit the brackets to any bed-post

within the compass of the same, notwithstanding the fact that the clamping-screws H are comparatively short. This is accomplished by the projections a a' on said clamping-arms engaging any of the notches or serrations E in said arm in a manner readily comprehended.

By constructing the brackets with the serrations or notches, as described, we derive advantages not obtainable by the brackets as now in use, one of such advantages being that it provides for better and quicker adjustment to fit the device to a bed-post, &c.

The arms A, clamps F, and sockets L, as well as all the other metallic parts of the holders, are readily produced in the process of casting in gray or malleable iron. They can also be readily coated with tin, nickel, &c., to improve their appearance and durability, and are thus produced at a very low figure.

Heretofore pillow-sham holders have been constructed with a socket on the end of the bars or slats, said socket having centrally a spindle or bolt upon which a further socket on the bracket engages, a spiral spring being placed into the interior of the latter socket and a nut on the bolt outside of the socket on the bracket arranged to keep the parts together. In this construction the serious drawbacks exist that the nut on the outside is liable to unscrew and then to allow the parts to disengage or to screw up tighter than originally adjusted, and then to immovably connect the parts, either of these accidents rendering the apparatus useless. Furthermore, the spiral spring in this device is not capable of adjustment, because by tightening the nut on the outside the parts are (as already mentioned) drawn into close contact. In our device these objections are overcome. The spring cannot cause the bolt in the slat to turn, while the latter bolt, by being tightened, draws the slat farther into the socket, and thereby increases the tension of said

spring and the friction upon the parts, without, however, interlocking them, so as to prevent their being readily moved when desired.

Having thus fully described our invention, we claim as new and desire to secure to us by Letters Patent of the United States—

1. In pillow-sham holders, the combination, with slotted arms A, having projecting claws B and lateral projecting heads C, of the L-shaped clamping-arm F, provided with the T-shaped projection G and catches a a', said catches being arranged to engage with serrations or notches E along the inner opposite edges of the slotted aperture D in said arm A, substantially as and for the object stated.

2. In pillow-sham holders, the combination, with the bars I I', of the socket-pieces L L', held in frictional contact with and projecting beyond the ends of said bars, as specified, to produce the chambers f, spiral springs M, thumb-screws N, and brackets A, having suitable heads, C, to operate in conjunction with said screws and spiral springs, substantially as and for the object described.

3. In pillow-sham holders, the combination, with a suitable bracket having heads C, with apertures c, of the slats I I', having tapering ends, the socket-pieces L L', fitted to and projecting over the ends of said slats or bars I I', to form an adjustable chamber, f, the spiral springs M, located in such chamber, and the bolts N, said bolts being constructed to draw the ends of the bars I I' farther into the sockets L L' to compress the springs M, as and for the object specified.

In testimony that we claim the foregoing as our invention we have hereunto set our hands this 7th day of June, 1888.

GEO. W. SCHIFFER.
ARTHUR L. KNIGHT.
